UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

WINDOW REGULATOR.

Application filed June 28, 1923. Serial No. 648,364.

This invention relates to a mechanism for raising and lowering windows, such mechanism being commonly known as window regulators, and the object of my invention is 5 the provision of a mechanism of the character described which is simple and inexpensive in its construction, is positive in operation, is easily operated to raise or lower the associated window, and is particularly adapted 10 for use in connection with the type of windows commonly used in closed automobiles and other vehicles, which windows have lowering movements when being opened.

The invention is fully described in the following specification, and while, in its broader aspect, it is capable of embodiment in numerous forms, a preferred embodiment thereof is illustrated in the accompanying drawings in which,—

20 Fig. 1 is an outer side elevation of the lower portion of an automobile door with part of the sheathing broken away to show the invention associated therewith and also showing the window in lowered position.

25 Fig. 2 is an enlarged fragmentary vertical sectional view of the door shown in Fig. 1 with the window in raised position.

Fig. 3 is an enlarged fragmentary sectional view showing the construction at the lower 30 end of the worm shaft.

Fig. 4 is an enlarged fragmentary sectional view of the mechanism at the upper end of the worm shaft including the operating handle, gears for turning the worm shaft, 35 and co-operating mechanism.

Fig. 5 is an enlarged sectional view showing the lower edge of the window in raised position, the window opening and associated parts.

40 Fig. 6 is a section taken on the line 6—6 of Fig. 1 and shows the means for holding the worm and worm wheel sector in alignment.

45 Referring to the drawings, 1 is an automobile door having a window opening 2 therein, and 3 designates a glass or window part which is adapted to be raised in position to close the opening 2 or to be lowered into the lower portion of the door, which is made 50 hollow for such purpose, as is customary in doors used in closed vehicles, as for instance, in automobiles.

55 The window or member 3 is adapted to rest freely at its lower edge on a roller 4, which is carried at the free end of a verti-

cally swinging arm 5. The arm 5 is fastened adjacent to its lower end to a segment 6 of a worm wheel, the segment 6 and the arm 5 being pivoted at 7, to a metal board 8 which extends substantially across the full width 60 of the door 1 and forms a part thereof for strengthening the same and entirely supporting the window regulator mechanism. A worm 9 formed on a vertical shaft 10 meshes with the segment 6. The lower end of the shaft 10 may be journaled in a bracket 11 which is secured by the screws 12 to the lower flanged edge of the metal board 8. A ball thrust bearing 13 is also provided as a seat 65 for the shaft 6 to take the downward thrust thereof, and a screw plug 14 threaded in the bracket 11 is to adjust the axial position of the shaft 10. The upper end of the shaft 10 may be reduced in size and is journaled in a member 15 which also supports the horizontal shaft 16 and a ball thrust bearing 17 held between the upper end of the vertical shaft 10 and the horizontal shaft 16 to take the upward thrust of the shaft 10. The member 15 70 may have a flange 18 which is adapted to bear against the inner surface of the metal board 8. The end of the member 15 adjacent the flange 18 projects through the board 8 and is recessed and threaded within the recess for a purpose hereinafter described. A 75 nut or clamping member 19 whose outwardly projecting flange 20 serves as an escutcheon plate for holding the upholstering material 21 against the board 8, has a projecting 80 threaded portion adapted to be threaded into the threaded end of the member 15 and thereby clamp the metal board 8 and the upholstering material 21 between the flanges 18 and 20 and also firmly secure the member 15 85 in place on the metal board 8. The nut or clamping member 19 has a central opening therethrough which serves as a journal and support for the horizontal shaft 16 which projects through the same and to which the handle 22 is suitably secured. A bevel gear 23, preferably of the spiral tooth type, is secured to the end of the horizontal shaft 16 90 opposite the handle 22 to turn therewith and also bear against the end of the member 15. A flange 24 on the horizontal shaft 16 seats against the bottom of the recess in the end of the member 15 and this in conjunction 95 with the gear 23 prevents longitudinal movement of the horizontal shaft 16. A bevel gear 25 secured to the shaft 10 adjacent its 100 105 110

upper end meshes with the gear 23 and is caused to turn therewith to operate the worm 9.

It is thus evident that the turning of the handle 22 rotates the shaft 16, gears 23 and 25, and worm shaft 10. When the handle 22 is turned, causing the worm 9 to turn therewith, the worm wheel sector 6 is caused to rotate about its pivot 7 in a direction dependent upon the direction of rotation of the handle 22. Inasmuch as the arm 5 is secured to the worm wheel sector 6, rotation of the handle causes the free end of the arm 5 to be raised or lowered, and the associated window 3 resting on the roller 4 is caused to move up or down in a corresponding manner. A coil spring 26 attached at one end to the upper flanged edge of the metal board 8 and at the other end to the arm 5 serves to counter-balance the weight of the window 3 resting on the roller 4 at the outer end of the arm 5, so that any strain due to the total weight of the window will be reduced and the mechanism will work freely and without friction.

The glass of the window 3 is provided with a channel shaped metal binding strip 27 at its lower edge which rests on the roller 4 of the arm 5. The upper outside edge of this strip 27 being flanged over and outwardly as at 28. The sheathing of the door 1 projects over the lower edge of the window opening 2 to a point adjacent the window 3 as at 29 and is then turned back on itself for a short distance and a flexible rubber strip 30 is placed beneath the same. When the window 3 is raised the rubber strip 30 is compressed between the flange 28 and the door sheathing at 29, to prevent water from passing from the outside of the window to the recess or pocket formed for the window and thus prevent damage to the window regulating mechanism.

A downwardly projecting member 31 having an inwardly turned flange at its lower edge is fastened to the binding strip 27, the inwardly turned flange passing below the roller 4 on the arm 5 so that in the event the window 3 becomes stuck or does not freely follow the roller 4 when the same is lowered, the roller 4 will bear against the inwardly turned flange of the member 31 and pull the window 3 with it to its lowered position.

The segment of the worm wheel 6 as shown in the drawings is preferably made of sheet metal to reduce weight and cost and in the event that the window 3 works rather hard in its guideways the segment 6 might bend out of the engagement with the worm 9 when an excessive strain is put on the mechanism to move the window 3 if means was not provided (see Fig. 6) for keeping the sector 6 and worm 9 at all times in proper alignment. This means comprises a block 32

secured to the metal board 8 in which is supported a ball-bearing 33 which bears against the side of the sector 6 adjacent its outer edge, the ball bearing 33 being free to rotate. A member 34 also secured to the metal board 8 passes out around the worm 9 and over the outer edge of the sector 6 and carries a ball-bearing 35 which seats freely between the member 34 and the sector 6 at a point on the opposite side of the sector 6 from the ball-bearing 33 but in a position corresponding therewith. The sector 6 is thus guided between the ball-bearings 33 and 35 which prevents it from bending sideways out of engagement with the worm 9. The arm 5 which is secured at its one end to the sector 6 to pivot therewith at 7, has its free end offset from the sector 6 so that upon rotation the arm will free the ball bearings 33 and 35 and the guide member 34 when the window 3 is raised to closed position.

It has heretofore been common practice in building window regulators to provide means for locking the operating handle against rotation when not being operated, to prevent the window from slipping down inadvertently. An important result obtained by the construction shown is that it is possible to do away with such locking mechanism as it is an inherent characteristic of a worm and wheel that the wheel is self locking when the thread angle of the worm is equal to, or smaller than, the angle of friction between the worm and wheel, the usual value of such thread angle being about $8\frac{1}{2}$ degrees.

Thus if the thread angle of the worm is $8\frac{1}{2}$ degrees or less there will be no danger of the window working down inadvertently. Should I desire to use a worm of a greater thread angle, any type of satisfactory handle locking device may be used for preventing the window from working down.

It is understood that formal changes may be made in the specific embodiment of this invention without departing from the spirit or substance of the broad invention, the scope of which is commensurate with the appended claims.

What I claim is:

1. The combination with a closure and its frame, of a supporting member extending across said frame, a lever pivoted at one end to said supporting member and supporting said closure at its free end, a segmental worm wheel secured to said lever and movable therewith, a vertical shaft supported by thrust bearings on said supporting member, a worm on said shaft meshing with said worm wheel, means to prevent displacement of said worm wheel in respect to said worm, means to rotate said shaft and thereby raise and lower said closure, and resilient means for counterbalancing the weight of said closure.

2. The combination with a closure member and its frame, of a lever pivoted at one end thereof to said frame and supporting said closure member at the free end thereof; a worm wheel sector connected to and movable with said lever; a shaft having a worm thereon meshing with said worm wheel sector; guides adjacent the toothed face of said worm wheel sector to prevent disengagement thereof in respect to said worm; thrust bearings for said worm; means for adjusting the axial position of said worm; a gear on said shaft; a gear on a second shaft meshing with said first mentioned gear and a handle on said second shaft to rotate said shaft and said gears.

3. The combination with a closure and its frame, of mechanism for raising and lowering said closure comprising a lever, a worm wheel sector, a worm, and means for rotating the same; and means for preventing displacement of said worm wheel in respect to said worm, said means comprising rotatable guides positioned adjacent the toothed face of said worm wheel sector.

4. The combination of a closure and a frame, of a metal board extending across the width of said frame adapted to support mechanism for raising and lowering said closure, said mechanism comprising a lever pivoted at one end to said metal board and carrying said closure at the free end thereof; a worm wheel sector secured to said lever; a shaft having a worm thereon meshing with said worm wheel sector and supported by said metal board; means for taking the thrust and for adjusting the axial position of said shaft; means for causing rotation of said shaft; and means for holding said worm wheel sector in proper relationship with said worm.

5. In a device of the class described, a hollow frame, a window slidably mounted in

said hollow frame, a lever pivoted at one end and supporting said window at its free end, a worm wheel sector secured to said lever, a worm operating in conjunction with said worm wheel, the thread angle of said worm being smaller than the angle of friction between said worm and worm wheel sector, means for causing rotation of said worm, and rotatable means to guide said worm wheel sector.

6. In a device of the class described, a hollow frame, a window slidably mounted in said hollow frame, a board extending across the width of said frame and forming a part thereof, a lever pivotally mounted at one end to said board and supporting said window at its free end, a segment of a worm wheel secured to said lever, a worm supported by said board meshing with said segment of the worm wheel, the thread angle of said worm being such that said worm wheel is irreversible or self locking and mechanism supported by said board for causing rotation of said worm.

7. In a closure operating mechanism, the combination with a slidably mounted closure member, of means for moving said closure member comprising a lever pivoted at one end and supporting said closure member at the other end thereof; a worm wheel sector secured to said lever adjacent its pivoted end; a worm meshing with said worm wheel sector; rotatable means for holding said worm wheel sector in alignment with said worm; and means for rotating said worm to thereby raise and lower said closure member.

Signed by me at Detroit, Michigan, U. S. A., this 22nd day of June, 1923.

JOSEPH H. BOURGON.
